C. W. DUNHAM.
RAILWAY SIGNALING.
APPLICATION FILED MAR. 26, 1920.

Patented June 7, 1921.

UNITED STATES PATENT OFFICE.

CHARLES W. DUNHAM, OF FAIRMONT, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,380,783.

Specification of Letters Patent. Patented June 7, 1921.

Continuation of application Serial No. 323,247, filed September 12, 1919. This application filed March 26, 1920. Serial No. 368,873.

To all whom it may concern:

Be it known that I, CHARLES W. DUNHAM, a citizen of the United States, residing at Fairmont, in the county of Allegheny and State of Pennsylvania, have invented certain new and useful Improvements in Railway Signaling, of which the following is a specification.

My invention relates to electrical apparatus, and particularly to apparatus comprising a polarized relay, a circuit for said relay including a source of current and a pole changer, and a second circuit controlled by the polarized relay.

One object of my invention is the provision of means for reducing the interval of time during which the second circuit is open while the polarized relay is responding to a reversal of the pole-changer.

Apparatus embodying my invention is particularly well adapted to the control of signals and other devices for governing the passage of cars or trains along a railway, although it is not limited to such adaptation.

The present application is a continuation of my co-pending application, filed September 12, 1919, Serial No. 323247, for railway signaling.

I will describe two forms of apparatus embodying my invention, and will then point out the novel features thereof in claims.

In the accompanying drawings Figure 1 is a diagrammatic view showing a signaling system having a signal controlled in accordance with one form of my invention, the holding magnet being a slow-releasing magnet having a very short time element. Fig. 2 is a fragmentary view similar to a portion of Fig. 1 but showing a modified form of apparatus in which the holding magnet is non-slow-releasing in character.

Similar reference characters refer to similar parts in each of the views.

Referring first to Fig. 1, the reference characters 2 and 2^a designate the track rails of a railway over which traffic normally moves in the direction indicated by the arrow. These rails are divided by insulated joints 3 into a plurality of sections of which only one section A—B is shown in the drawing. The section A—B is provided with a track circuit comprising, as usual, the track rails of the section, a battery 5 connected

across the rails at the exit end of the section, 55 and a track relay 6 connected across the rails at the entrance end of the section.

Located adjacent the entrance end of section A—B is a signal S^B governing traffic through this section, and arranged to indicate stop, caution and proceed. This signal is controlled by a polarized relay R, which, in turn, is controlled by the track relay 6 and by a pole-changer E operated by a signal S^A located at the entrance end of the section to the left of section A—B. The circuit for this polarized relay R is from a battery 39, through wire 7, pole-changer P, wire 8, contact 9 of track relay 6, wires 10 and 10^a, winding of relay R, wires 11 and 12, pole-changer P, and wire 13 to battery 39. When signal S^A is in the stop position, the polarity of the current supplied to relay R is such that polarized contact 28 of this relay is open, and this current I will term 70 current of reverse polarity. When signal S^A is in the caution or proceed position, the pole-changer P is in the opposite position, so that current of normal polarity is supplied to relay R. This current causes the 75 polarized contact 28 to close. Of course, when track relay 6 is open, as shown in the drawing, relay R is deenergized, so that its neutral front contact 15 is open and its neutral back contact 34 is closed. Relay R is so 80 constructed that when it becomes deenergized after having been energized by current of normal polarity, the polarized contact 28 remains closed.

The signal S^B comprises a semaphore 4 90 biased to the stop position, an electric motor M for moving the semaphore to the caution and proceed positions, and a holding magnet H for holding this semaphore in the two last-mentioned positions. This magnet 95 H is a slow-releasing magnet having a very short time element.

The operation of the parts thus far referred to, is as follows:

Section A—B is occupied by a car or train 100 represented by a pair of wheels and an axle V, so that track relay 6 is open and polarized relay R is deenergized. All circuits for the control of the motor and holding magnet for signal S^B are, consequently, open, 105 so that the semaphore 4 of this signal is in the stop position. I will now assume that the car or train V passes out of section

A—B and into the section next to the left. Track relay 6 then closes, but the movement of signal S^A to the stop position due to the train entering the next section causes pole-changer P to reverse, so that current of reverse polarity is supplied to relay R. The neutral front contact 15 of this relay then closes a circuit through the holding magnet H, which circuit is from battery 40, through wires 14 and 14^a, contact 15, wires 16, 17 and 18, contact 19^a—19, wire 20, magnet H, and wires 21 and 23 to battery 40. Contact 15 of relay R also closes a circuit for inotor M, this circuit being from battery 40, through wires 14 and 14^a, contact 15, wires 16, 17 and 24, contact 25^a—25, wire 26, motor M, and wires 27 and 23 to battery 40. Motor M then operates to move semaphore 4 to its caution or inclined position, at which point the circuit for the motor is opened because the wiper 25 passes off of the fixed contact member 25^a. The signal is held in the caution position, however, by magnet H, which continues to be energized.

25 When the car or train in the section to the left of section A—B passes out of such section, signal S^A will move to the caution or proceed position, so that pole-changer P will be reversed, whereupon current of normal polarity will be supplied to the polarized relay R, causing contact 28 of this relay to close. The reversal of the polarity of the current supplied to relay R causes contact 15 to open momentarily, thus momentarily opening the circuit for magnet H; for present purposes, however, I will assume that this does not cause magnet H to release the semaphore 4 from the caution position. A new circuit for motor M is then closed, this circuit being from battery 40, through wires 14 and 14^a, contacts 15 and 28, wires 29 and 31, contact 25^a—25, wire 26, motor M, and wires 27 and 23 to battery 40. The motor M then moves the 45 semaphore toward the proceed position, the magnet H being energized during the first part of such movement by the same circuit as before. After the semaphore has moved a short distance, however, a new circuit for magnet H becomes closed at contact 19—19^b, this circuit being from battery 40 through wires 14 and 14^a, contact 15, polarized contact 28, wires 29 and 30, contact 19^b—19, wire 20, magnet H, and wires 21 and 23 to battery 40. When the semaphore reaches the proceed position, the wiper 25 passes off of contact segment 25^b, so that the motor becomes deenergized. The semaphore is held in this position, however, by magnet H.

60 The operation of the signal S^B when a car or train enters section A—B, will be readily understood without explanation.

As I have already pointed out, when the signal S^B is in the caution position and the 65 polarity of the current supplied to the po-

larized relay R is reversed, the neutral front contact 15 of this relay is momentarily opened. The time element or lag of magnet H is less than the time contact 15 is open during the reversal of pole-changer P, and so it follows that during this reversal magnet H will release unless means are provided to prevent such action. The means here shown for preventing the release of the holding magnet comprises an auxiliary relay C, which relay is connected in multiple with relay R and is controlled by a neutral back contact 34 of the latter relay. The circuit for this relay C is from battery 39, through wire 7, pole-changer P, wire 8, contact 9, wires 10 and 32, relay C, wire 33, contact 34, wire 12, pole-changer P, and wire 13 to battery 39. The caution circuit for holding magnet H is provided with a branch around contact 15 of the polarized relay R, which branch passes from wire 14, through wire 38, front contact 37 of auxiliary relay C, and wire 36 to wire 17.

The operation of this portion of the apparatus is as follows. It is, of course, understood that when pole-changer P reverses, the time interval during which the circuit for relay R is open is very short, being in fact only a small fraction of a second. Furthermore, the characteristics of relay R and the circuit in which it is included are such that when the pole-changer reverses, back contact 34 closes at substantially the same instant that the circuit for relay R is reclosed at the pole-changer. Relay C will 90 therefore close very soon after back contact 34 closes, because the lag of this relay is very small, but front contact 15 of relay R will not close for a considerable time after its back contact 34 closes because the lag of 95 this relay is considerable owing to the reversal of flux in the magnetic circuit of the relay. Magnet H is so designed that its lag or time element is slightly greater than the time between the opening of front contact 100 15 and the closing of back contact 34 during reversal of pole-changer P (which time is extremely small and almost immeasurable), plus the time required for contact 37 to close 105 after contact 34 closes. When the parts are 110 so designed, it is evident that magnet H will not release the signal while relay R is open due to reversal of pole-changer P. I have found that the desired result may be secured by making the time element of magnet H as small as 0.15 second, which is considerably less than the time that contact 115 15 is open during reversal of the pole-changer. Relay C, of course, opens as soon as relay R closes.

The main advantage of my invention lies 120 in the fact that when a train enters a section, the signal for such section responds by moving to the stop position much more quickly 125 than is the case when a slow-releasing mag-

net or relay of the usual character having a time element of about 1.5 seconds is employed.

It will be noted that relay C consumes no energy except during the brief interval in which relay R is open immediately after an operation of pole-changer P.

It will be observed that relay C is energized from the same source of current as relay R, so that if this source should fail, relay C will not become energized.

Referring now to Fig. 2, the parts here shown are the same as the corresponding parts shown in Fig. 1, except that the magnet H^a is non-slow-releasing in character, and means are provided for placing this magnet on short circuit while the signal is in the caution position and the back contacts of relay R and C are closed. The short circuit path for magnet H^a is from one terminal of this magnet through wires 21 and 22, wire 41, back contact 42 of relay C, wire 43, back contact 15 of relay R, wires 16, 17 and 18, contact 19^a—19, and wire 20 to magnet H^a. The control of the relays R and C is the same as in Fig. 1, and the control of the signal by these relays is likewise the same as in Fig. 1, except for the short-circuiting feature.

As stated above in discussing Fig. 1, after current is supplied to relay C a certain interval of time elapses before front contact 37 closes. The greater part of this interval is consumed in setting up flux in the magnetic circuit of the relay, however, and during this part of the interval back contact 42 remains closed. The interval between the opening of back contact 42 and the closing of front contact 37 is so extremely small that it cannot readily be measured. It will be seen, therefore, that during the greater part of the time interval of relay C, magnet H^a is on short circuit. It is well understood that when a magnet is deenergized and is immediately placed on short circuit it will hold its armature for a considerable interval of time, this interval being longer than the interval between the closing of back contact 15 and the opening of back contact 42.

As for relay R, the interval of time between the opening of the front point of contact 15 and the closing of the back point of this contact is extremely short—too short to be readily measureable.

It will now be seen that magnet H^a is on open circuit during the time between the opening of the front point of contact 15 and the closing of the back point of this contact, that the magnet is on short circuit during the interval between the closing of the back point of contact 15 and the opening of back contact 42, and that it is on open circuit, during the time between the opening of back contact 42 and the closing of front contact 37. I have found that an

ordinary quick releasing magnet will hold its armature during this cycle of operations.

The real difference between Figs. 1 and 2, is, of course, that in Fig. 2 the time interval of relay C is virtually eliminated insofar as its effect on the holding magnet is concerned by placing this magnet on short circuit during such interval.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a polarized relay, a circuit for said relay including a source of current, means for reversing the polarity of the current supplied to said relay from said source, a second relay, a circuit for said second relay controlled by a neutral back contact of said polarized relay, means for opening and closing said two circuits simultaneously, and another circuit controlled by a neutral front contact of said polarized relay and a front contact of said second relay in multiple.

2. In combination, a polarized relay, a circuit for said relay including a source of current, means included in said circuit for reversing the polarity of the current supplied to said relay from said source, a second relay, a circuit for said second relay including said source of current and a neutral back contact of said polarized relay, and another circuit controlled by a neutral front contact of said polarized relay and a front contact of said second relay in multiple.

3. In combination, a polarized relay, a circuit for said relay including a source of current, means included in said circuit for reversing the polarity of the current supplied to said relay from said source, a second relay, means controlled by said polarized relay for energizing said second relay when the polarized relay is open during response of the latter relay to reversal of the polarity of the current supplied thereto, and a circuit controlled by a neutral front contact of said polarized relay and a front contact of said second relay in multiple.

4. In combination, a polarized relay, a circuit for said relay including a source of current, means included in said circuit for reversing the polarity of the current supplied to said relay from said source, a second relay, means controlled by said polarized relay for energizing said second relay when the polarized relay is open during response of the latter relay to reversal of the polarity of the current supplied thereto, a signal having a semaphore biased to one position and a magnet for holding the semaphore in an

other position against the biasing force, and a circuit for said magnet controlled by a neutral front contact of said polarized relay and a front contact of said second relay in 5 multiple.

5. A signaling system comprising a section of railway track, a track circuit for said section including a track relay, a polarized relay controlled by said track relay, means controlled by traffic conditions in advance of 10 said section for supplying said polarized relay with current of one polarity or the other, a signal for said section controlled by neutral and polarized contacts of said 15 polarized relay, an auxiliary relay connected in multiple with said polarized relay and controlled by a neutral back contact of the latter relay, and a branch around the neutral contact of said polarized relay in the circuits 20 for said signal said branch including a front contact of said auxiliary relay.

6. In combination, a polarized relay, a circuit for said relay including a source of current, means included in said circuit for 25 reversing the polarity of the current supplied to said relay from said source, a second relay, means controlled by said polarized relay for energizing said second relay when the polarized relay is open during 30 response of the latter relay to the reversal of the polarity of the current supplied thereto, a signal controlled by a neutral front contact of said polarized relay and a front contact of said second relay in multiple, and 35 means including a back contact of each of said relays for placing said signal on short circuit.

7. In combination, a polarized relay, a circuit for said relay including a source of current, means included in said circuit for 40 reversing the polarity of the current supplied to said relay from said source, a second relay, means controlled by said polarized relay for energizing said second relay 45 when the polarized relay is open during response of the latter relay to reversal of the polarity of the current supplied thereto,

a signal having a semaphore biased to one position and a magnet for holding the semaphore in another position against the biasing force, a circuit for said magnet controlled by a neutral front contact of said polarized relay and a front contact of said second relay in multiple, and means for placing said magnet on short circuit comprising a back contact on each of said relays. 50 55

8. In combination, a polarized relay, a circuit for said relay including a source of current, means for reversing the polarity of the current supplied to said relay from 60 said source, a second relay, a circuit for said second relay controlled by a neutral back contact of said polarized relay, means for opening and closing said two circuits simultaneously, and a signal controlled by a 65 neutral front contact of said polarized relay and a front contact of said second relay in multiple.

9. In combination, a polarized relay, a circuit for said relay including a source of 70 current, means included in said circuit for reversing the polarity of the current supplied to said relay from said source, a second relay, a circuit for said second relay including said source of current and a neutral back contact of said polarized relay, and a signal controlled by a neutral front contact of said polarized relay and a front contact of said second relay in multiple. 75

10. In combination, a polarized relay, a circuit for said relay including a source of current, means included in said circuit for reversing the polarity of the current supplied to said relay from said source, a second relay, means controlled by said polarized relay for energizing said second relay 80 when the polarized relay is open during response of the latter relay to reversal of the polarity of the current supplied thereto, and a signal controlled by a neutral front contact of said polarized relay and a front contact of said second relay in multiple. 85 90

In testimony whereof I affix my signature.
CHARLES W. DUNHAM.
